P. A. MEEHAN

TUNNEL KILN

Filed March 26, 1920

INVENTOR

Paul S. Neuhause
BY
John E. Bubbell
his ATTORNEY

UNITED STATES PATENT OFFICE.

PAUL A. MEEHAN, OF NEW CASTLE, PENNSYLVANIA, ASSIGNOR TO AMERICAN DRESSLER TUNNEL KILNS, INC., OF NEW YORK, N. Y., A CORPORATION OF NEW YORK.

TUNNEL KILN.

Application filed March 26, 1920. Serial No. 368,887.

To all whom it may concern:

Be it known that I, PAUL A. MEEHAN, a citizen of the United States, and resident of New Castle, in the county of Lawrence and State of Pennsylvania, have invented certain new and useful Improvements in Tunnel Kilns, of which the following is a specification.

I have invented certain new and useful 10 improvements in tunnel kilns, of which the following is a specification:

My invention relates to kilns of the type specially adapted for firing or annealing articles of glass and other material. The 15 objects of my invention are:—

1. To facilitate the loading of trucks designed to carry the articles to be fired or annealed through the kiln.

2. To preliminarily heat the goods to the 20 required temperature before introducing them into the kiln.

3. So far as concerns the kiln proper, a construction which will permit of the generation of the highest temperature at the 25 entrance of the kiln with a gradually diminishing temperature to the exit of the kiln.

The accompanying drawings will serve to illustrate my invention in which Fig. 1 is 30 a horizontal section through the kiln and preliminary heating chamber;

Fig. 2 is a vertical section taken on the line II—II of Fig. 1, and

Fig. 3 is a vertical section taken on the line III—III of Fig. 1.

5 In the drawings 5 indicates the body of the kiln, which may be of any suitable construction, and 6 the pre-heating chamber. Situated within the body of the kiln are combustion chambers 7. These combustion 10 chambers may be of any suitable type preferably, however, they are of the kind described in the prior patent of C. Dressler, No. 1,170,428, dated February 1, 1916.

The combustion chambers 7 are situated 15 in the forward end of the kiln 5 and carried backwards past the median line. Their length, however, may be varied in accordance with circumstances. Located in line with the combustion chambers in the 20 rear end of the kiln are cooling tubes 8, the general relation of the combustion chambers and the cooling tubes being substantially that shown in patent of C. Dressler, No. 1,023,628, dated April 16, 1912. To heat 25 the combustion chambers gas burners 9 are

provided at the forward end of the combustion chambers. The products of combustion from the chambers 7 are carried off through flues 10 from the combustion chambers proper and through the cooling tubes 60 8 and exit flues 10' from the latter. The exit flues 10 are provided with regulating dampers 11.

Situated at the forward end of the kiln is 65 the pre-heating chamber 6, which is shown as a cylindrical structure in the bottom of which is a platform or turntable 12, mounted on supporting wheels 13. The platform carries pairs of rails 14, and 15, the rails 70 14 being at right angles to rails 15.

Located within the chamber 6 is a vertical 75 tube 18, the lower end of which connects with a flue 19 connected with the exhaust flues 10 and 10' from the combustion chambers 7. Connected to the flue 19 are hollow 80 metallic wings 20, the lower ends of which are connected through flues 21 to the interior of a drum 22 mounted on the platform 12 and rotating with the latter. The lower end of the drum 22 communicates 85 with flue 23 which discharges into the atmosphere. It will be seen from the description that products of combustion passing through the flues 10, 10' and 19 into the flue 18 and thence through wings 20, flues 21 and drum 22 heat the interior of 90 the chamber 6. An annular sand seal 31 surrounds the pipe 18 and another sand seal 32 surrounds the ports communicating with the flue 23. Pipes 33 are provided for passing sand into the troughs of seals 31 and 32.

Located within the kiln 5, are the tracks 100 16 over which goods carrying trucks 25, see Fig. 3, are adapted to move. The tracks 16 communicate at opposite ends of the furnace respectively with turn tables 26 and 27. The turn table 26 communicates at the forward end of the kiln with the tracks 17 and the turn table 27 at the rear end with tracks 24. A turn table 29 connects the tracks 27 to the return tracks 28 running to the preheating chamber 6. The preheating chamber is provided with doors 30 at the positions A, B, C, D. In the preferred mode of operation contemplated A is 105 the loading position; B the heating position; C the delivery position; D the car take on position. Assuming the door in position A to be open, the truck 25 can be loaded when in that position, or alternately, the truck 110

- 25 may be drawn out of the preheating chamber and loaded. When the truck is fully loaded, the platform 12 is rotated in the direction of the arrows which brings the truck 25 at the position D into the position A, and the trucks formerly in the position A into the position B. When the second truck is loaded and the platform again rotates, the truck in the position B is carried into the position C, and then moved out of the preheating chamber along the rails 17 on to turn table 26, then on to rails 16 and into the kiln, through the kiln to turn table 27, on to rails 24 to the turn table 29, on to the rails 28 and thence back into the preheating chamber through the door 30 at D. I do not limit myself to the exact way from tracks to turn tables as described. Other arrangements will suggest themselves which will be equally as desirable to obtain the required movements of the trucks. It will be observed that in the arrangement disclosed the preheating chamber and kiln proper are so separated that there is no continuity in the atmospheric conditions therein such as exists between the atmospheric conditions in the adjacent heating and drying zones of kilns in which such zones are formed by adjacent sections of a continuous kiln chamber with no door or partition between the zones.
- Having now described my invention, what I claim as new and desire to secure by Letters Patent, is:
1. The combination with a tunnel kiln and its heating means, of an independent preheating chamber, together with means for heating the preheating chamber by the hot products of combustion from the kiln heating means.
2. The combination with a tunnel kiln, of a rotary preheating chamber, together with means for heating said chamber with the waste heat from the kiln.
3. The combination with the tunnel kiln, having closed combustion chambers therein, of a preheating chamber so separated from the kiln that the atmospheric conditions in the kiln and preheating chamber are discontinuous, and a heating device in said preheating chamber, together with means for connecting the interior of the combustion chambers of the kiln with the heating device in the preheating chamber.
4. The combination with a tunnel kiln, of a preheating chamber, means for heating the preheating chamber with waste heat from the kiln, together with intervening track ways and turn tables, and trucks thereon, whereby truck carried goods may be heated in the preliminary heating chamber, and progres-
- sively moved through the kiln and back to the preliminary heating chamber.
5. The combination with a tunnel kiln, of a preliminary heating chamber having a series of doorways, a rotary platform and track ways thereon and external trackways connecting with the platform trackways through said doorways.
6. The combination with a tunnel kiln, of a combustion chamber situated at the forward end of said kiln, means for introducing gas and air into the forward end of said combustion chamber, a preheating chamber so separated from the kiln that the atmospheric conditions in the kiln and preheating chamber are discontinuous, means for introducing the waste heat from the tunnel kiln into the preheating chamber, a series of goods carrying trucks and means for introducing said trucks progressively into said preheating chamber and moving them progressively out of said preliminary heating chamber into the tunnel kiln.
7. The combination with a tunnel kiln, of a preliminary heating chamber comprising an enclosed rotary platform.
8. The combination with a tunnel kiln, of a preliminary heating chamber comprising an enclosed turntable, a heating device mounted on said turntable and a waste heat flue leading from said kiln and connected to said heating device.
9. The combination with a tunnel kiln, of an auxiliary heating chamber comprising an enclosed turn table having track ways crossing one another and adapted to receive a plurality of goods carrying cars at a time, of heating means carried by said turntable with supply and discharge connections passing centrally through the turn table, and a waste heat flue from the kiln communicating with said supply connection.
10. The combination with a tunnel kiln having a trackway therethrough for goods carrying cars, of trackways external to the kiln for returning said cars from the exit to the entrance end of the kiln and comprising an enclosed turntable adapted to receive a plurality of cars at a time.
11. The combination with a tunnel kiln having a trackway therethrough for goods carrying cars, of trackways external to the kiln for returning said cars from the exit to the entrance end of the kiln and comprising an enclosed turntable adapted to receive a plurality of cars at a time, and means for heating the cars on said enclosed turntable.

Signed at New Castle in the county of Lawrence and State of Penna., this 20th day of March, A. D. 1920.

PAUL A. MEEHAN.
